UNITED STATES PATENT OFFICE.

JOHN M. HAMILTON, OF CUMBERLAND, MARYLAND.

ADJUSTABLE SHADE-BRACKET.

No. 918,849.

Specification of Letters Patent.

Patented April 20, 1909.

Application filed July 10, 1908. Serial No. 442,924.

To all whom it may concern:

Be it known that I, JOHN M. HAMILTON, a citizen of the United States, residing at Cumberland, in the county of Allegany and State 5 of Maryland, have invented a new and useful Improvement in Adjustable Shade-Brackets, of which the following is a specification.

This invention relates to an adjustable shade bracket the object being to provide a 10 shade bracket which can be easily and quickly adjusted to suit any length roller whereby the disadvantages now existing with shade brackets will be overcome.

Another object of my invention is to provide a bracket with an adjustable arm which 15 is held in its adjusted position by the tension of a pair of flat springs so that it is only necessary to press the arm inwardly and move it into adjusted position whereby it will be 20 locked.

A further object of the invention is to provide the arm with a revoluble disk having a plurality of different size openings to receive the pintle or stud pin of a shade roller, as the 25 case may be.

A still further object of my invention is to provide an adjustable shade bracket which is exceedingly cheap in construction and one which is so constructed that the supporting 30 arm can be quickly adjusted and locked in its adjusted position without operating any screws or pins.

Another object of the invention is to provide a shade bracket which is so constructed 35 that it can be used for supporting either end of the shade roller.

With these various objects in view, my invention consists in the novel features of construction and arrangement of parts herein- 40 after described and claimed.

In the drawings forming a part of this specification: Figure 1 is a perspective view of my improved shade bracket showing it applied to a window frame. Fig. 2 is a section on line 2—2 of Fig. 1. Fig. 3 is a section on 45 line 3—3 of Fig. 1. Fig. 4 is a longitudinal section of the bracket, and Fig. 5 is a perspective view detached.

In carrying out my invention I employ a 50 pair of brackets A, A' which are formed exactly alike, the description of one being sufficient for both. The brackets are adapted to be secured to the window frame as clearly shown in Fig. 1.

Referring more particularly to the drawing, B indicates the bracket proper which is

provided with suitable openings through which screws are adapted to pass for securing it to the frame. The bracket is provided with angled portions C forming a guide-way 60 the inner face of which is cut to form a rack C' and the outer face enlarged as shown at C² on which are secured the ends of flat springs D which bear against the enlarged ends E' of arms E² formed on a supporting arm E which 65 is provided with oppositely disposed shoulders E⁴ for guiding and preventing the arm from being pushed too far inwardly as will be hereinafter fully described. The enlarged portions E' are provided with central teeth 70 E⁵ which are held into engagement with the racked portion C' of the guide-way by the flat springs and it will be seen that to adjust the arm in the bracket it is only necessary to push inwardly on the arm so as to throw the 75 teeth out of engagement with the rack which will allow the arm to be moved longitudinally in the guide-way so that it can be quickly adjusted to suit different size window shades.

The arm E is provided with an oblong opening E³ adapted to register with openings formed in a disk F pivotally mounted on the arm, the disk being provided with a pair of oblong openings F¹ of different sizes and a 85 pair of round openings F² of different sizes, the round openings being adapted to receive the pintle of the curtain shade and the oblong openings to receive the stud pin of the spring end of the curtain shade, and it will 90 be seen that by this arrangement either of the openings can be readily turned so as to bring it in alinement with the opening of the arm so that either end of the curtain roller can be placed within the bracket.

In Fig. 1, I have shown a right and left bracket the only difference being that the disk with the openings are mounted on the inner faces of the arms so as to receive the respective end of the rollers and it will be 100 seen that after the pintle or stud pin of the roller has been placed in the openings and the arms forced together it will be impossible for the roller to accidentally become detached from the brackets, thereby overcoming the difficulties now existing of pulling the whole curtain down when drawing the shade down.

From the foregoing description, it will be seen that I have provided very novel means 110 for holding the supporting arms in their adjusted positions whereby the curtain will be

securely locked in an operating position after once being put in place so that all danger of the curtain becoming accidentally detached from the arms is prevented.

5. What I claim is:—

1. The combination with a pair of brackets provided with guide-ways, of arms slidably mounted in said guide-ways provided with openings, disks pivotally mounted on 10 said arms provided with openings to receive the pintle and stud pins of the curtain roller and means for locking said arms in their adjusted positions.

2. A shade bracket comprising a bracket 15 proper provided with a guide-way having a racked inner face, an arm slidably mounted in said guide-way provided with teeth for engaging said rack, flat springs arranged to the rear of the rack for holding said teeth in 20 engagement with the rack and a disk pivotally mounted on the arm provided with openings to receive either the pintle or the stud pin of a shade roller.

3. The combination with a pair of brackets 25 provided with guide-ways having racked inner faces, flat springs arranged to the rear of said racked faces and spaced therefrom, supporting arms provided with toothed portions arranged between the rack and springs

of said guide-ways, said toothed portions 30 being held in engagement with the rack by the flat springs, and disks pivotally mounted on the arms provided with openings of different sizes to receive the pintle end or stud pin 35 of the shade roller.

4. A curtain shade bracket comprising a bracket proper having angled portions forming a guide-way, the inner faces of which are provided with racked portions, the ends of 40 said guide-ways being provided with enlargements, flat springs secured on said enlargements and spaced from said racked portions, a supporting arm provided with oppositely disposed arms at its end having enlarged portions provided with teeth arranged 45 between the racked portions and flat springs, oppositely disposed shoulders formed on said arm for limiting the inward movement of the arm and a disk provided with oblong openings of different sizes and round openings of 50 different sizes pivotally mounted on said arm adapted to align with an oblong opening formed therein.

JOHN M. HAMILTON.
